W. A. RINGLER

DISPENSING CARTON

Filed June 21, 1923

Patented June 3, 1924.

1,496,491

UNITED STATES PATENT OFFICE.

WILLIAM A. RINGLER, OF PHILADELPHIA, PENNSYLVANIA.

DISPENSING CARTON.

Application filed June 21, 1923. Serial No. 646,759.

To all whom it may concern:

Be it known that I, WILLIAM A. RINGLER, a citizen of the United States, residing at Philadelphia, county of Philadelphia, State 5 of Pennsylvania, have invented a new and useful Dispensing Carton, of which the following is a specification.

The ordinary types of paper cups are usually sold in cartons from which they are 10 removed by the customer, so that it is difficult to maintain them in a sanitary condition until used as they are liable on removal from the carton to collect dirt, dust and foreign material.

15 It is the object of my present invention to devise a novel dispensing carton in which the articles will be concealed until dispensed and from which one article at a time can be withdrawn.

20 With the above in view my invention comprehends a novel construction of a dispensing carton.

It further comprehends a novel dispensing carton wherein the usual type of carton, 25 having sealable ends, is provided at one end with resilient or elastic means which co-operate to support a series of superimposed articles and to permit them to be withdrawn one at a time.

It further comprehends a novel dispensing carton having its ends adapted to be sealed, provided with means to receive a supporting device and also provided with a resilient article retaining member.

35 Other novel features of construction and advantage will hereinafter clearly appear in the detailed description and the appended claims.

For the purpose of illustrating the invention, I have shown in the accompanying drawings a preferred embodiment which in practice has given satisfactory and reliable results. It is, however, to be understood that the various instrumentalities of which my 45 invention consists can be variously arranged and organized and that the invention is not limited to the precise construction and arrangement of these instrumentalities as herein set forth.

50 Figure 1 represents a perspective view of a dispensing carton, embodying my invention, in knock down form.

Figure 2 is a perspective view of the sealed carton.

55 Figure 3 is a section on line 3—3 of Figure 2.

Figure 4 is a section on line 4—4 of Figure 1.

Figure 5 is a section on line 5—5 of Figure 3. 60

Figure 6 is a perspective view of the dispensing portion of the carton in detached position.

Figure 7 is a plan view of the holder for the resilient article retainer and dispenser. 65

Similar numerals of reference indicate corresponding parts.

Referring to the drawings.

1 designates a paper carton, embodying my invention. The carton may have any 70 desired form or contour but usually, in practice, consists of a rectangular shaped carton having at each end the foldable flaps 2 and the covering and locking flap 3. The ends of the carton are sealed, if desired, by means of the strips 4 which are provided with adhesive and arranged at an angle to each other so that one of them extends over the other.

In order that the carton can be readily attached to a support, I secure to a side of the carton, near one end, a reinforcing member 5 having an opening 6, so that the carton may be pierced by a lead pencil, ice pick or other suitable device, so that the carton can 80 be hung on a nail or other type of fastener 7 carried by a fixed support, such as the wall of a room or a desk. 8 is the support for a resilient article retainer and 9 is the article retainer co-operating therewith. The support 8 is in the form of a strip of material, 85 preferably flat, and adapted to carry the retainer 8. This strip is provided with weakened lines 10 and slits 11 which preferably but not necessarily terminate in apertures 12. 90

The cartons are usually made out of paper or cardboard and the support 8 may be made out of similar material. 13 designates the articles to be dispensed and if such 100 articles are paper cups, they are nested one within another, and each has the conventional outwardly extending flange or bead at its upper end. 14 designates a strip of flexible material. 105

The carton without the dispensing mechanism is made in the usual way.

The retainer support is cut out and provided with the weakened lines and with the slits and a resilient retainer is inserted in 110 such slits, as will be understood from Figure 6. A strip of flexible material may or

may not be placed diagonal within the support 8. The dispenser is then pressed together and pasted, glued or otherwise fastened to the inner walls of the carton at 5 one end, and the carton is ready to receive the articles to be dispensed. The carton in a knockdown condition is opened to its final form, the flexible strip 14 facilitating the opening of the dispenser carrying portion. The articles are now placed in the 10 carton, both ends are sealed, as before explained, and the carton is ready for the market.

When the customer desires to use an article 15 he breaks the seal at the dispensing end and opens out the end flaps. All of the articles move downwardly so that the uppermost article is below the aperture 6 and the flange or bead of the lowermost article 20 will be supported on the resilient retainer 9, see Figure 3.

The carton is now hung up on a nail or similar support. The intending user takes hold of the lowermost article and draws it 25 downwardly until it is released by the resilient retainer 9 and the next superposed article engages and is supported by the retainer 9. The retainer 9 may be in the form of an ordinary elastic band and, as 30 illustrated, has four supporting portions on which the cup flanges rest. I preferably have at least two supporting portions on the retainer 9 but one or more such supporting portions may be employed.

35 It will be apparent that in the preferred form of my invention I employ an elastic band which is preferably endless and when the dispensing device is in the carton the elastic band is under tension so that there 40 will be a uniform action against the bead, flange or lip of the cup. As the lowermost cup is drawn downwardly, the elastic band will slide over the bead, flange or lip of the cup which is being withdrawn, and due 45 to the tension of the band will engage the bead, flange or lip of the superimposed nested cup. The elastic or resilient retainer may however, be made of any desired material and has the double function of supporting the stack of nested articles and also

to provide for the dispensing of one article at a time from the container or carton within which they are placed.

Having thus described my invention, what I claim as new and desire to secure 55 by Letters Patent, is:

1. In a cup dispensing carton, the combination with a carton having an opening at one end, of a stack of nested cups in said carton, and a resilient retainer and dispenser in the form of an elastic band carried by and within the carton and engaging the lowermost cup.

2. In a cup dispensing carton having an opening at one end and means to seal said 65 opening, of a stack of nested cups in said carton, and an endless resilient retainer secured within the carton adjacent said opening and under tension and engaging the upper portion of the lowermost cup to support the stack and to permit only one cup at a time to be withdrawn from said carton.

3. A paper cup dispenser, comprising a carton having an opening at one end, through which the cups are dispensed and 75 having means to close said opening, of an elastic band secured within said carton adjacent said opening, and a reinforcing member secured to said carton and adapted to receive a supporting device whereby the 80 carton can be supported in proximity to the supply of liquid for said cups.

4. A paper cup dispenser comprising a carton rectangular in cross section, having an opening at one end through which the 85 cups are dispensed and having means to close said opening, a reinforcing strip rectangular in cross section secured within said carton adjacent to said opening and having slits at its corner portions, and an 90 elastic band in said slits whereby four elastic portions are provided on which the cups are supported, said elastic band contacting with the lowermost cup and serving to prevent more than one cup being withdrawn 95 at a time.

WILLIAM A. RINGLER.
